UNITED STATES PATENT OFFICE.

JOSEPH H. BOURGON, OF DETROIT, MICHIGAN, ASSIGNOR TO THE STUDEBAKER CORPORATION, OF SOUTH BEND, INDIANA, AND DETROIT, MICHIGAN, A CORPORATION OF NEW JERSEY.

TOP CONSTRUCTION.

Application filed November 20, 1924. Serial No. 751,154.

This invention relates to tops for motor vehicles and the like and particularly to tops of the permanent type.

One of the objects of the present invention is to provide a top of novel and improved construction, the main portion of which is composed of sheet metal to make it strong and durable and to which the various other top members and adjuncts may be applied to form a permanent unitary structure.

Another object is to provide a top frame constructed from a continuous sheet of metal of such a construction that the top of which it forms a part will not be subject to the "drumming" usually associated with tops of this type.

Another object is to provide a sheet metal automobile top frame with a plurality of relatively large openings in the upper surface thereof, the metal at the edge of the openings being downwardly bent to give added strength and stiffness to the top.

A further object is to provide a top frame of the class described with relatively large openings in the upper surface thereof, the metal at the edge of said openings being downwardly turned to form attaching flanges for strengthening ribs or tacking strips.

The above being among the objects of the present invention, the same consists of certain features of construction and combinations of parts to be hereinafter described with reference to the accompanying drawing, and then claimed, having the above and other objects in view.

In the accompanying drawing, which illustrates a suitable embodiment of the present invention, and in which like numerals refer to like parts throughout the several views,

Figure 1 is a perspective view of a finished automobile top constructed in accordance with the present invention as it may appear on an open type automobile.

Figure 2 is a perspective view of the frame of the top shown in Figure 1 before the top covering and top supports have been applied thereto.

Figure 3 is a broken perspective view of a portion of the top frame including one of the openings therein showing the manner

of securing the strengthening ribs or tacking strips thereto with the top lining in place.

Figure 4 is a longitudinal vertical section of the top frame taken centrally through one of the rows of the openings.

Figure 5 is an enlarged transverse sectional view of a portion of one side of the top frame of Figure 2, showing the manner in which the lower edge is turned in to form a flange for receiving the edge tacking strip.

The top frame as shown in Figure 2, which is an improvement of the ordinary top frame, is formed preferably from a single continuous sheet of metal into the desired shape and contour, but in the following description and claims which will refer to the top frame as being constructed from a continuous sheet of metal, it will be kept in mind that the present invention is not limited to a metal top frame which is constructed from a single sheet of metal, as it is applicable to and includes those constructions where the same are made up of a plurality of units welded, riveted or otherwise suitably secured together to form a continuous sheet, and has the same practical results and effects as a frame constructed from a single sheet.

Top frames constructed from a continuous sheet of metal have had but a limited use in the past due to the fact that these early designs had a tendency to vibrate in unison, to a highly objectionable degree, with other vibrations present in the automobile of which they formed a part, or with the explosions of the engine, in much the same way that a drum head may be made to vibrate in sympathy with independent vibrations. Another great objection to the former tops occurred when the top was distorted or by "weaving" as the automobile of which it formed a part traveled over rough or uneven surfaces, because of stresses of various characters being set up in the metal with the resulting tendency for the metal to temporarily change its shape, which frequently caused snapping or crackling sounds much the same as are produced upon pressing the bottom of an oil-can. In the present invention I have eliminated such disadvantages and objections as appeared in the former type of top and have

provided a structure which will present flexibility with the body but not lose the advantages of a permanent top.

As mentioned above, the metal of the top frame 10 is formed from a continuous sheet of metal into the desired shape and contour, that is, to the shape of conventional tops as shown in Figures 1 and 2, or otherwise, but preferably such that no flat spots are present anywhere on its surface to better eliminate any drumming sound that may develop.

As illustrated in Figures 2 and 4 a wooden front cross member 11 is provided in the construction shown to more easily secure a rain-shield 12 or windshield 13 thereto, but this may be dispensed with and the metal of the top 10 be extended to take its place. At frequent intervals in the upper and flattest surface of the frame 10 relatively large openings 14 are provided which prevent the "drumming" of the top with the same result as is experienced when openings are cut in a drum head, that is, the openings 14 substantially eliminate all vibrations in the top. In addition to eliminating the tendency of the top 10 to drum or vibrate, the openings 14 also act to break up any stresses that may be set up in the metal when the top "weaves", inasmuch as no stress can be transmitted through the openings, and the result of thus breaking up the stresses set up in the metal is the elimination of the snapping or crackling sounds.

It has been found desirable to turn the edges of the metal surrounding the openings 14 downwardly perpendicular to the plane of the top to form flanges 15 to assist in strengthening the top. These flanges 15 act to give the frame 10 more strength in a plane perpendicular to the plane thereof and thereby eliminate the tendency to drum, and they also form ready means for attaching wooden strips such as 16 to the top, which strips 16 may be extended across the inside of the frame 10 to act as stiffening ribs or tacking strips for the top lining 17.

The number, shape and size of the openings 14, as well as the depth of the flanges 15, may vary according to the needs of the various shapes, sizes and contours of the tops in which they are used and the most desirable dimensions will probably be best found by experimentation, although the number of openings and formation thereof as shown have proven satisfactory.

As shown in Figure 5, it is preferable to turn the lower edge of the frame 10 inwardly to form a horizontally extending flange 18

to which may conveniently be secured the wooden strip 19 which may be utilized for a variety of different purposes such as a tacking strip for the top outer covering or the like.

Although the frame 10 as shown in Figure 2 is illustrated as applied to an open type of automobile body 20 in Figure 1, it will be apparent without further discussion that it may equally well be applied to bodies of the closed type with equal advantages.

Formal changes may be made in the specific embodiment of the invention described without departing from the spirit or substance of the broad invention, the scope of which is commensurate with the appended claims.

What I claim is:—

1. A vehicle top frame formed from a continuous sheet of metal, the upper portion of said frame being provided with a plurality of openings extending transversely thereof, the metal at the edge of said openings being bent downwardly out of the plane of said openings, cross ribs secured to said downwardly projecting edges, and a top lining spaced from said frame secured to said cross ribs.

2. In a vehicle top frame, a continuous sheet of metal formed to substantially the shape of the finished top, the upper portion of said sheet being provided with a plurality of relatively large openings therein, the metal at the edge of said openings being downwardly turned to form attaching flanges, and cross ribs secured to said flanges.

3. In combination with a vehicle top, a frame formed to substantially the shape of the finished top from a continuous sheet of metal, relatively large openings formed in the upper portion thereof in spaced relation, the metal at the edge of said openings being downwardly turned to form attaching flanges, tacking strips secured to said flanges, and a covering within said top to conceal said openings secured to said tacking strips.

4. In a vehicle top, a frame comprising a continuous sheet of metal formed to substantially the shape of a finished top, having a flange at its lower edge and a plurality of relatively large openings formed in the upper surface thereof, the metal at the edges of said openings being turned downwardly to form stiffening members and tacking strips secured to a side of said downwardly turned members.

Signed by me at Detroit, Michigan, U. S. A., this 17th day of November, 1924.

JOSEPH H. BOURGON.
